UNITED STATES PATENT OFFICE.

DAVID FITZPATRICK, OF CLEVELAND, OHIO, ASSIGNOR TO THE CLEVELAND WORM AND GEAR COMPANY, OF CLEVELAND, OHIO, A CORPORATION OF OHIO.

WORM-GEAR.

1,358,191.

Specification of Letters Patent.

Patented Nov. 9, 1920.

Application filed January 4, 1918, Serial No. 210,388. Renewed September 8, 1920. Serial No. 409,038.

To all whom it may concern:

Be it known that I, DAVID FITZPATRICK, a subject of Great Britain, and resident of Cleveland, in the county of Cuyahoga and 5 State of Ohio, have invented certain new and useful Improvements in Worm-Gears, of which the following is a specification.

My invention relates in general to a wheel having an outer ring formed of material 10 different from that of the body or center of the wheel and relates more particularly to a modified form of the gear wheel that is shown in my co-pending application, Serial No. 77,361 filed February 10, 1916.

15 The object of this invention is to produce a wheel comprising a center of relatively strong material such as cast iron having a peripheral groove with substantially continuous shoulders and suitable passages 20 communicating with said groove and an outer ring of relatively weak material such as bronze or similar material that is cast onto the center and permanently secured thereto.

25 Various other objects and advantages of the invention will be in part obvious from an inspection of the accompanying drawings and in part will be more fully set forth in the following particular description of 30 one form of mechanism embodying my invention, and the invention also consists in certain new and novel features of construction and combination of parts hereinafter set forth and claimed.

35 In the accompanying drawings:

Figure 1 is a side elevation partly in section of a gear wheel embodying my invention.

40 Fig. 2 is a front view partly in section of the gear wheel.

The center A of the wheel may be of cast iron, malleable iron, steel or suitable alloy. The rim or periphery of the center is provided with a central annular groove B. 45 This groove B is relatively narrow and is limited by sharply defined shoulders C that are practically continuous except for small transverse slots D which are spaced at considerable intervals to provide additional 50 anchorage for the cast metal ring. A plurality of locking loops or openings E are provided in the rim and communicate with the groove at each end. These loops may communicate with the side of the wheel 55 through small passages F that are bored

through the side of the wheel preferably near the lower or innermost portion of the loop. One such exterior opening is provided for each of the locking loops.

A ring H of relatively weak anti-friction metal such as bronze or similar alloy is cast around the periphery of the wheel. The metal flows into the locking loops or openings and also into the side passages and securely anchors the ring into the center or 60 core.

After the ring has been cast in place suitable teeth are cut in the periphery of the ring which may be of any desired character. My invention being particularly 70 adapted for use with worm gears but spur gears or any other type may be made.

The shoulders formed by the annular groove hold the ring securely against lateral movement, and the locking loops prevent 75 any creeping or circumferential movement. The loops are further reinforced by the lateral plug of metal that extends through the side opening provided in the rim. This opening also serves the purpose of preventing the formation of air pockets when the ring is cast. The bronze is cast onto the core in the usual way at a single casting operation and an extremely strong and rigid construction is provided with a 80 limited use of the relatively expensive bronze or other anti-friction metal.

While I have shown and described, and have pointed out in the annexed claims, certain novel features of my invention, it will 90 be understood that various omissions, substitutions and changes in the form and details of the device illustrated and in its operation may be made by those skilled in the art without departing from the spirit of the 95 invention.

Having thus described my invention, I claim:

1. A gear wheel having a center of comparatively strong metal with an annular 100 shoulder on its outer face and a cast ring of comparatively weak anti-friction material on said center in engagement with said shoulder, one of said parts having also projections entering openings in the other and 105 extending toward the axis.

2. A gear having a center of comparatively strong metal with an annular groove on its outer face and a plurality of openings 110 in the rim communicating with said groove,

- and a cast ring of comparatively weak anti-friction material on said center in engagement with said groove, said cast ring having projections entering said openings.
- 5   3. A gear having a center of cast iron with an annular shoulder on its outer face and a plurality of openings extending toward the axis, said openings communicating with a side of the center through a passage
- 10   approximately parallel to the axis, and a cast ring of comparatively weak anti-fric-

tion material on said center in engagement with said shoulder, said ring having projections entering the openings in the said center.

15

Signed at St. Petersburg in the county of Pinellas and State of Florida this 21st day of December A. D. 1917.

DAVID FITZPATRICK.
